(57) **CLAIM**

The ornamental design for a tile trim, as shown and described.

DESCRIPTION

FIG. 1 is a top perspective view of a first embodiment of a tile trim, showing my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a top perspective view of a second embodiment of a tile trim, showing my new design.

FIG. 9 is a front elevational view thereof.

FIG. 10 is a rear elevational view thereof.

FIG. 11 is a left side elevational view thereof.

FIG. 12 is a right side elevational view thereof.

FIG. 13 is a top plan view thereof.

FIG. 14 is a bottom plan view thereof.

FIG. 15 is a top perspective view of a third embodiment of a tile trim, showing my new design.

FIG. 16 is a front elevational view thereof.

FIG. 17 is a rear elevational view thereof.

FIG. 18 is a left side elevational view thereof.

FIG. 19 is a right side elevational view thereof.

FIG. 20 is a top plan view thereof.

FIG. 21 is a bottom plan view thereof.

FIG. 22 is a top perspective view of a fourth embodiment of a tile trim, showing my new design.

FIG. 23 is a front elevational view thereof.

FIG. 24 is a rear elevational view thereof.

FIG. 25 is a left side elevational view thereof.

FIG. 26 is a right side elevational view thereof.

FIG. 27 is a top plan view thereof; and,

FIG. 28 is a bottom plan view thereof.

The broken lines showing holes in the tile trim are for the purpose of illustrating environmental structure and unclaimed subject matter and form no part of the claimed design.

The tile trim is shown with a symbolic break in its length. The appearance of any portion of the article between the break lines forms no part of the claimed design.
